ABSTRACT

High quality centrifugally cast cylindrical members are obtained by varying the rate of rotation of the metal pouring ladle during casting to obtain a more rapid angular displacement of the ladle at the initiation and termination of the pour than at the middle of the pour. Because the weight of the molten metal tending to discharge the metal from the ladle varies inversely with angular displacement of the ladle, i.e., the weight of molten metal at the discharge lip is maximum at the middle of the pour cycle, a substantially constant volume of metal is discharged throughout the pour. In a preferred embodiment of this invention, the rate of displacement of the ladle during the pour is symmetrical with the rate of ladle displacement being reduced from a predetermined speed during the first half of the pour and gradually increased to approximately the initial ladle displacement rate over the second half of the pour.

APPARATUS FOR POURING MOLTEN METAL FROM A LADLE

This invention relates to a method and apparatus for pouring molten metal from a ladle during centrifugal casting. More specifically, the invention relates to a variable speed ladle rotation mechanism for producing a more rapid rotation of the ladle at the initiation and termination of the pour than at the middle of the pour to produce a constant volumetric flow of metal from the ladle.

In the centrifugal casting of cylindrical structures, a quantity of molten metal typically is deposited in a ladle and, after insertion of the ladle into the rotating mold, and ladle is rotated to discharge the molten metal from the ladle into the mold for solidification. In order to obtain a high quality cast structure, it generally is desirable to rotate the ladle gradually to obtain a uniform pour from the initial discharge of molten metal from the ladle to the termination of the pour. Although the desirability of a uniform pour heretofore has been known, see for example U.S. Pat. No. 1,917,872, the method utilized for obtaining the uniform pour normally has been the admission of a fluid, such as air, at a constant rate to the rotary drive mechanism for the ladle to produce a constant rate of angular displacement of the ladle. Although casts of good quality heretofore have been achieved utilizing constant ladle displacement rates, I have discovered that superior quality in cast cylindrical objects can be obtained by decreasing the angular displacement of the ladle during the first half of the pouring cycle. Although the exact reason for this phenomenon is not known with certainty, it is postulated that the weight of molten material at the discharge spout of the ladle increases during the initial half of the pour to discharge a substantially constant volume of material from the ladle with time.

It is therefore an object of this invention to provide a ladle rotating mechanism for centrifugally casting structures of superior quality.

It is also an object of this invention to provide a ladle rotation mechanism capable of obtaining a substantially constant discharge rate of molten metal from a ladle.

It is a further object of this invention to provide a method of centrifugally casting cylindrical structures while maintaining the discharge of molten metal from the ladle substantially constant.

As was heretofore stated, these and other objects of this invention generally are achieved by varying the rate of the ladle rotation during a single pour to produce a more rapid angular displacement of the ladle at the initiation of the pour than at the middle of the pour. Thus, a ladle rotating mechanism in accordance with this invention would include a vessel, such as a cylindrical ladle, capable of retaining molten material therein for a predetermined period of time and means for pouring of the molten material from an orifice situated in the upper portion of the vessel. The ladle rotating mechanism also contains means for controlling the rotational rate of the ladle during a single pour to reduce the speed of the angular displacement of the ladle during the first half of the pour and gradually increase the rotational speed of the ladle during the second half of the pour to produce a substantially continuous volume of metal flow from the ladle during the complete pour cycle.

While this invention is described with particularity in the appended claims, a more complete understanding of the invention may be obtained from the following detailed description of a specific embodiment of the invention when taken in conjunction with the appended drawings wherein:

FIG. 1 is an elevational view of a rotatable ladle in accordance with this invention;

FIG. 2 is a view of the ladle rotation mechanism utilized to pour molten metal from the ladle;

FIG. 3 is a view of the control mechanism employed for obtaining a variable angular displacement rate in the ladle;

FIG. 4 is a graph illustrating the variation of the rate of angular displacement of the ladle with the pour cycle, and

FIG. 5 is a pictorial illustration depicting the deposition of molten metal within the ladle at various stages of the pour.

20 A ladle 10 having a controlled rate of angular displacement in accordance with this invention is illustrated in FIG. 1 and generally comprises a cylindrical vessel 12 secured to the end of shaft 14 proximate mold 16 to deposit molten material, e.g., liquid aluminum, 25 into the rotating mold to cast a cylindrical structure, such as a finned motor frame. The vessel is carried upon a carriage 18 which is axially traversable along rails 20 to insert the vessel within the mold whereafter the vessel is rotated by rotational mechanism 22 secured to the end of shaft 14 remote from the ladle. A rotational mechanism for applying controlled torque to vessel 12 and a carriage for insertion of the ladle within the rotating mold is described in co-pending U.S. application, Ser. No. 277,920 entitled "Horizontal Centrifugal Casting Machine" filed in the name of F. W. Baumann et al and assigned to the assignee of the present invention, (the entire disclosure of which application is incorporated herein by reference).

40 Cylindrical vessel 12 preferably has an exterior metallic sheathing 24 and an inner ceramic lining 26 to maintain the molten metal within the vessel at elevated temperatures prior to casting. In conventional fashion, a rectangular opening 28 is provided in the upper surface of the cylindrical vessel to permit filling of the vessel and the subsequent controlled discharge of molten metal from the vessel. Typically, opening 28 extends at least 70 percent of the length of the vessel to equalize the pour region over an elongated axial length of the mold and the longitudinal sides of the opening are spaced by a span, typically between 40° and 90°, permitting a rapid pour of molten metal from the vessel. It will be appreciated, however, that other geometric configurations also could be utilized for the ladle to be controllably rotated in accordance with the teachings of this invention. For example, rather than a rectangular opening in the vessel, the entire upper portion of vessel 12 could be removed. Alternatively, the ladle could be a rotatable cup like vessel mounted upon a rotatable shaft and having a side pour spout upon the upper lip of the vessel for the discharge of metal from the vessel.

45 Referring more particularly to FIG. 2, rotational mechanism 22 for the ladle basically includes a hydraulic cylinder 30 for driving a rod 32 meshed with a pinion 34 fixedly mounted upon shaft 14. The drive force for the rod is provided by hydraulic fluid admitted to cylinder 30 from source 36 through valve 38 disposed

in hose 40 interconnecting the cylinder with the hydraulic fluid source. As hydraulic fluid is admitted to cylinder 30, rod 32 is driven outwardly from the cylinder to rotate cylindrical vessel 12 and pour molten metal from the vessel into the mold.

In accordance with this invention, the rate of admission of hydraulic fluid to cylinder 30 is varied during the pour to obtain a uniform rate of molten metal discharge from ladle 10. As can be seen in FIG. 3, the variable rate of angular displacement of the ladle is obtained by a tapered cam 42 which engages control unit 44 of valve 38 to vary the orifice within the valve to produce a faster rate of angular displacement of the ladle at the initiation and termination of the pour than at the middle of the pour (as is shown in the graph of FIG. 4). Thus, rather than using a continuous rate of angular displacement of the ladle, the ladle is rotated at a rapid, preferably uniform, rate at the initiation of the pour of molten metal from rectangular opening 28 and the rate of ladle rotation is gradually decreased along line A until approximately one-half of the molten metal within the ladle is discharged from the ladle. At such time, the upwardly tapered face 46 of cam 42 engages control unit 44 to gradually increase the rate of hydraulic fluid flow to hydraulic cylinder 30 and the rate of rotation of the ladle is increased along line B to return the ladle at the termination of the pour to approximately the rate of rotation at the initiation of the pour.

By varying the ladle rotation rate in the foregoing manner, the volume of metal per unit time discharged from the ladle is substantially constant throughout the pour and the quality of the cast structure is improved relative to cast structures formed by tilting the ladle at a uniform displacement rate. Furthermore, because the rate of rotation of the ladle is reduced at the middle of the pour, the amount of splashing in the mold is reduced. In general, the maximum rate of ladle displacement and the change in the rate of ladle rotation will vary dependent upon such factors as the size of the rectangular opening of the ladle, the height of the molten metal in the ladle, the interior configuration of the mold, etc., and can best be determined empirically for each frame size to be cast by a particular ladle.

At the initiation of a pour cycle, vessel 12 is filled (as shown in FIG. 5A) and roller 48 of control unit 44 is engaged by cam 42 at surface 50 (perpendicular to the traversal path of the control unit) to admit hydraulic fluid to cylinder 30 at a rate to produce a rapid, substantially constant angular displacement of the ladle. When the vessel, however, has rotated to a position (as illustrated in FIG. 5B whereat the molten metal is at the discharge lip 52 of rectangular opening 28), downwardly tapered face 54 of cam 42 begins to engage roller 48 and the volume of hydraulic fluid admitted to the cylinder is gradually reduced, preferably in an approximately linear fashion, until about one-half of the molten metal within the vessel is discharged from the vessel (as shown in FIG. 5C). At such time, upwardly tapered face 46 engages the roller of the control unit and the flow of hydraulic fluid through the control unit is gradually increased to increase the rate of rotation of the ladle. Preferably, the control unit is positioned relative to the cam so that the final rotational speed of the ladle upon discharge of molten metal therefrom (as shown in

FIG. 5D) is approximately equal to the rotational speed of the ladle at the initiation of the discharge.

While a specific embodiment of this invention has been illustrated and described, it will be obvious to those skilled in the art that many variations can be made in the structural features of the rotating mechanism without departing from the scope of this invention. For example, rather than employing a tapered cam fixedly secured to rod 32 to regulate control unit 44, the cam could be a circular cam mounted upon shaft 14 to engage roller 48 of the control unit. I intend therefore by the appended claims to cover all such modifications and changes as fall within the true spirit and scope of this invention.

What I claim as new and desire to secure by Letters Patent of the United States is:

1. In a ladle rotating mechanism for use in pouring a predetermined volume of molten metal into a centrifugal casting mold, the combination of a ladle (10) rotatably mounted upon a movable carriage (18), a centrifugal mold (16) operably mounted proximate said carriage, said carriage being operable to insert the ladle into said mold in response to the carriage being moved toward the mold, a rotational mechanism (22) coupled to the ladle for applying torque to rotate it at a controlled rate, thereby to afford a predetermined variable rate of angular displacement of the ladle, a control unit (44) operatively coupled to the rotational mechanism to control the rate of rotation thereof, a tapered cam (42) mounted on said rotational mechanism for relative movement with respect to said control unit, said cam being in engagement with a cam follower (48) that is operably coupled to the control unit (44) to cause it to vary the rate of angular displacement of the ladle in response to the cam follower being moved relative to the control unit, said tapered cam being operable in combination with the cam follower, control unit and rotational mechanism to produce a rapid angular displacement of the ladle at the initiation of a pour cycle followed by a generally linear reduction in the rate of rotation of the ladle unit approximately one-half of the predetermined volume of metal in the ladle is discharged, followed by a generally linear increase in the rate of rotation of the ladle during the latter half of the pour cycle until the rate of rotation approximates that achieved at the initiation of the pour cycle.

2. A ladle rotating mechanism according to claim 1 wherein said ladle is a cylindrical vessel (12) having an axis of rotation disposed in a substantially horizontal plane and having an orifice (28) comprising a generally rectangular opening therein, and wherein said control unit for varying the rate of rotation includes a cam actuated valve that is connected to a pressurized source of fluid to vary the rate of flow of the fluid for applying torque to said ladle.

3. An invention as defined in claim 1 wherein said tapered cam has a pair of linearly tapered surfaces (46, 54) that define a V-shape for controlling the movement of the cam follower, said V-shaped surfaces being disposed between a pair of linear surfaces that extend beyond the outer ends of the tapered surfaces in a plane that is substantially perpendicular to the vertical axis of said V-shape.
